UNITED STATES PATENT OFFICE.

CHARLES A. BONNEY, OF ST. LOUIS, MISSOURI, ASSIGNOR TO UNITED SHOE MACHINERY COMPANY, A CORPORATION OF NEW JERSEY.

FLY-CLOSER FOR BUTTON-SHOES.

1,108,423.

Specification of Letters Patent.

Patented Aug. 25, 1914.

Application filed August 16, 1909. Serial No. 513,128.

To all whom it may concern:

Be it known that I, CHARLES A. BONNEY, a citizen of the United States, residing at St. Louis, in the State of Missouri, have invented certain Improvements in Fly-Closers for Button-Shoes, of which the following description, in connection with the accompanying drawings, is a specification, like reference characters on the drawings indicating like parts in the several figures.

This invention relates to fly-closers to hold together the opposite flies of a shoe upper by engagement with the lining of the upper and its object is to improve devices of this class. In fly closers of this type such as is shown in the co-pending application Serial No. 526,859, it is desirable to provide a device which shall engage the lining by piercing it, which device may be quickly attached or detached, which may be detached while the flies are under tension and which also will be economical to manufacture and simple to operate.

To this end a feature of the present invention consists in a fly-closer capable of having its lining engaging means forced into engaging position at a single operation and capable of being detached while the flies are under tension also by a single movement.

Further features consist in means to strengthen the lining engaging members and to limit the extent to which the members will penetrate the lining, which means also assist in preventing the device from becoming accidentally detached.

In the preferred embodiment of the invention herein shown, a detachable fly-closer is provided, comprising two members hinged back to back, each of said members consisting of a single wire pointed at both ends to form outwardly projecting points and bent to provide a hinge seat and a strengthening bar, which bar also serves to limit the extent to which the points will penetrate the lining and assists in preventing the device from becoming accidentally detached. An advantage of this preferred construction is that the hinge permits the members to be appropriately inclined to each other so that the projecting points of each member will be forced simultaneously into engagement with the lining as the device is moved toward the lining and the hinge straightened. When in operative position the strengthening bars will prevent

the device from sliding bodily in either direction a sufficient distance to disengage the projecting points. This fly-closer may be applied to button shoes or to lace shoes, and whether being lasted right side out or inside out. As herein shown the fly-closer is applied to a button shoe being lasted inside out as is common in making "turn" shoes, so called.

In the drawings, Figure 1 is a top plan view of a device embodying the invention, in place upon the lining of a button shoe about to be lasted; Fig. 2 is a plan view of one of the twin sections of which the device is composed; Fig. 3 is a top plan view of the device of the invention.

As shown in the drawings, the device preferably comprises the twin sections 4-4, which are pivoted together by the clasp 5. Each of the sections 4 is preferably made from a single wire having pointed ends 6-6 which are parallel when the device has been folded as illustrated in Fig. 2, forming one long prong 7, one short prong 8, an overlapping fold or strengthening bar 9 and the hinge-bearing 10. The overlapping portion 9, where the wire is folded upon itself, may be covered by a metallic sheet 11.

The device is employed by thrusting all of the four projecting ends 6-6 into the lining 12 of the upper of a shoe, the prongs 7 and 8 being inserted in the lining 12 in such manner that the said prongs are parallel with the lining edges 13-13. The device remains thus inserted during the process of lasting and is then readily removed by elevating the clasp 5 and withdrawing the prongs 6-6.

Having thus fully described my invention, what I claim as new and desire to have secured to me by the grant of Letters Patent, is:

1. A fly-closer for button shoes comprising two members hinged back-to-back, each of said members being provided with a pair of outwardly projecting parallel points, said points being adapted to pierce the lining of a shoe.

2. A fly-closer for button shoes comprising two members hinged back-to-back, each of said members consisting of a single wire pointed at both ends and bent upon itself to provide a hinge-seat; and a strengthening bar for said two projecting parallel points, substantially as described.

3. A fly-closer for shoes comprising two members having their adjacent ends hinged together in parallel relation, each of said members being provided with projecting points arranged to pierce the lining of a shoe, and means extending in substantially parallel relation to the hinged portions of said member to limit the extent of penetration of said points.
- 10 4. A fly-closer for shoes comprising two members hinged together, each member formed substantially in a single plane and having a pair of points arranged to penetrate respectively the linings of opposite flies of the shoe.
- 15 5. A fly-closer, constructed and arranged to be detached while the flies are under tension, having a pair of members hinged together, each member having devices arranged to pierce respectively the linings of opposite flies upon a relative turning movement of said members toward parallel relation.
- 20 6. A fly-closer, constructed and arranged to be detached while the flies are under tension, comprising two members hinged together, each member having points to pierce the lining of opposite flies and means extending across each member from one side to the other to limit the extent of penetration of said points.
- 25 7. A fly-closer comprising twin sections each having at its outer end a pair of outwardly projecting prongs formed substantially in the plane of said section and arranged to pierce respectively opposite fly linings, and the said sections at their inner ends being hinged together back to back to permit all of their projecting prongs to be
- thrust into the said fly linings in operative position simultaneously upon straightening the hinge.
8. A fly-closer comprising twin sections each provided at opposite sides with means for piercing respectively opposite fly linings, and locking means for retaining the piercing means in operative position comprising opposed bars extending transversely of the said sections from one of said first named means to the other.
- 45 9. A fly-closer comprising twin sections each having at its outer end a pair of outwardly projecting prongs to pierce the lining of opposite flies, the said sections being hinged together at their inner ends and being provided with opposed bars connecting the said pairs of projecting prongs for retaining the said prongs in operative position while the hinge is straightened and until the hinge is again bent to detach the 50 said prongs from the work.
- 55 10. A detachable fly-closer comprising members hinged back to back, each of said members comprising a continuous wire pointed at both ends to form outwardly 55 projecting prongs, each of said wires being bent to provide a hinge seat and further bent upon itself between the said hinge seat and its ends to form a transverse strengthening bar.
- 60 70 In testimony whereof, I have signed my name to this specification, in presence of two subscribing witnesses.

CHARLES A. BONNEY.
